PACKAGE HOLDER

Joseph P. McEnery, New York, N. Y.

Application March 12, 1941, Serial No. 382,938

6 Claims. (CL. 248—346)

This invention relates to package holders and more especially to holders for use with cigarette packages or the like which are provided with a wrapper so folded at the bottom as to provide a thin passage of the same width as the package leading from one side to the other.

An object of this invention is a simple, inexpensive and easily operated holder having a base and one or more tongues associated therewith in such manner as to extend into or through the passageway to secure the package to the base.

In one embodiment of the invention, the base is of such design as to provide a recess for receiving the bottom of the package and is provided with one or more slides equipped with a tongue adapted to be inserted into one end of the passageway at the bottom of the package to secure the latter to the holder. Preferably, the holder is rotatably attached to a support and interconnecting means are provided on the slide or slides and the support, whereby rotation of the holder relative to the support is effective to reciprocate the slide or slides to locate the tongue or tongues beyond one or both ends of the passageway and then move the tongue or tongues into one or both ends of the passageway to secure the package to the holder.

Other objects, novel features and advantages of this invention will become apparent from the following specification and accompanying drawings, wherein:

Fig. 1 is a perspective view of a holder embodying the invention;

Fig. 2 is a plan view with the base in one position relative to the support;

Fig. 3 is a view similar to Fig. 2 with the base in a different position relative to the support than that shown in Fig. 2;

Fig. 4 is a section on the line 4—4 of Fig. 2;

Fig. 5 is a section on the line 5—5 of Fig. 2, and

Fig. 6 is a perspective view of the slides.

In the embodiment herein disclosed, the frame or base 10 is preferably composed of molded plastic material and is of rectangular configuration. The frame is formed with a central rectangular recess 11 at the ends of which are provided transverse slots 12. The frame is pivotally attached to a support 13 through the medium of a stud 14 formed integral with the frame, the stud being locked to the support 13 by a resilient split ring collar 15 fitting in a groove in the stud.

The support 13 comprises a hollow box-like member having a removable bottom member 16, provided with hinge loops 17. A plate 18 has hinged loops 19 in alignment with the hinge loops

17 and also the support 13 is provided with apertured ears 20 also in alignment with the hinge loops 17. A hinge pin 21 extends through the ears 20 and hinge loops 19 and 17 and is provided with means, not shown, for adjusting the friction between the plate 18 and the support 13 for the purpose later to be described.

A pair of slides 22 engage the support 13 and at their outer ends are provided with tongues 23, each of which extends through a slot 12, the inner ends of the tongues preferably being slightly upturned and slightly tapered. Each slide is provided with an elongated transverse slot 24 into which projects a pin 25 carried by the support 13. The arrangement of the slots 24 is such that rotation of the frame or base 10 relative to the support 13 causes reciprocation of the slides 22. Each of the slides 22 is provided with a struck-up tab 26 which engages the under face of the bottom of the frame recess to steady the slides during their back and forth movement.

Fig. 2 illustrates the normal or holding position of the slides and tongues while Fig. 3 illustrates the releasing position of the slides and tongues. In order to associate a cigarette package with the holder, the bottom end of the cigarette package is introduced into the base recess with the base in the position shown in Figs. 2 and 5. The package is then oriented about its longitudinal axis to swing the base into the position shown in Fig. 3. Such swinging movement of the base causes outward movement of the slides 22 to move the tongues beyond the ends of the bottom passageway of the cigarette package. Next, the cigarette package is turned reversely to bring the base back to the position shown in Fig. 2. Such return movement of the base causes inward movement of the slides 22 to locate the tongues 23 in the ends of the bottom passageway of the cigarette package and hold it firmly in position.

Fig. 1 illustrates a use to which the holder may be put. For this use, the plate 18 is projected into the window-frame of an automobile door and is provided with a locking tab 18a for holding it in such position. The support 13 may be swung between a position in which it is aligned with the plate 18 or is at right angles thereto, the latter position being shown in Figs. 1 and 4. A cigarette package may be inserted in the base 50 when the support 13 is aligned with the plate 18 as previously described, after which the support may be returned to the position shown in Fig. 1. The friction previously referred to existing between the plate 18 and the holder is sufficient to maintain the holder in any position of adjust-

ment. Thus, when the holder is not in use, it may be swung down against the inner face of the door, but when in use is arranged perpendicular thereto and is held in such position by friction.

I claim:

1. A holder for packages having a bottom passageway leading from one side to the other, said holder comprising a base having a recess to receive the bottom of the package, a tongue associated with said base and adapted to enter one end of said passageway, a slide supported by said base and having a tongue adapted to enter the other end of said passageway, a support, a pivotal connection between said base and said support, and inter-engaging means on said slide and said support for effecting to and fro movement of said slide upon angular movement of said base relative to said support.

2. A holder for packages having a bottom passageway leading from one side to the other, said holder comprising a base having a recess to receive the bottom of the package, two slides supported by said base for movement toward and away from each other and having tongues adapted to enter opposite ends of said passageway, and means for effecting movement of said slides toward and away from each other.

3. A holder for packages having a bottom passageway leading from one side to the other, said holder comprising a base having a recess to receive the bottom of the package, two slides supported by said base for movement toward and away from each other and having tongues adapted to enter opposite ends of said passageway, a support, means pivotally connecting said base to said support, and inter-engaging means on said support and slides for effecting movement of the

latter toward and away from each other upon angular movement of said base relative to said support.

4. A holder for packages having a bottom passageway leading from one side to the other, said holder comprising a base having a recess to receive the bottom of the package, two slides supported by said base for movement toward and away from each other and having tongues adapted to enter opposite ends of said passageway, a support, means pivotally connecting said base to said support, and means including a pin and slot interconnecting each slide with said base, said slots being so angulated as to effect movement of said slides toward and away from each other upon rotation of said base relative to said support.

5. A holder for packages having a bottom passageway leading from one side to the other, said holder comprising a base having a recess to receive the bottom of the package, a tongue associated with said base and adapted to enter one end of said passageway, a slide supported by said base having a tongue adapted to enter the other end of said passageway, and means rotatable relative to said base for effecting reciprocation of said slide.

6. A holder for packages having a bottom passageway leading from one side to the other, said holder comprising a base having a recess to receive the bottom of the package, two slides supported by said base for movement toward and away from each other and having tongues adapted to enter opposite ends of said passageway, and means rotatable relative to said base for effecting movement of said slides toward and away from each other.

JOSEPH P. McENERY.
